Primary Examiner — Lilyana Bekic*Assistant Examiner* — Courtney J Clark-Rasheed(74) *Attorney, Agent, or Firm* — Ming Jiang; OPENPTO
US LLC(57) **CLAIM**

The ornamental design for a combined straw and scent device as shown and described.

DESCRIPTION

FIG. 1 is a front, top, and left perspective view of a combined straw and scent device showing my new design; FIG. 2 is a rear, bottom and left perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a partially enlarged view of an area 9 shown in FIG. 1; and, FIG. 10 is a partially enlarged view of an area 10 shown in FIG. 10. Shading in the drawings is used to show surface contour and does not represent color or texture.
